UNITED STATES PATENT OFFICE

SAMUEL C. CROSS, OF WEST SPRINGFIELD, MASSACHUSETTS, ASSIGNOR TO MOORE DROP FORGING COMPANY, OF SPRINGFIELD, MASSACHUSETTS, A CORPORATION OF MASSACHUSETTS

DIE FOR SWAGING MACHINES

Original application filed March 28, 1929, Serial No. 350,563. Divided and this application filed November 18, 1929. Serial No. 407,986.

This is a division of my application filed March 28, 1929, under Serial No. 350,563, and relates more particularly to improvements in swaging machines. The present invention 5 is illustrated in connection with the standard type of Dayton-Torrington rotary swaging machines.

In these rotary swaging machines, the reciprocating hammers and dies are carried in 10 a planetary travel around the work being operated upon so that the swaging operation on the work has been confined to the formation of surfaces round in cross section. Moreover, it is customary in such machines 15 to introduce and withdraw the work during the continuous operation of the machine and consequently the work performed is usually of a tapered formation.

The purpose of the present invention is to 20 increase the utility of such machines by enabling work of flat, irregular and non-round shape to be swaged. In general, this is accomplished by the provision of rotative bearing surfaces between the backs of the separable dies and the faces of the reciprocating hammers, whereby the hammers may partake of their usual planetary movement and the dies will be given a hammering action 25 against the work but otherwise may remain 30 in fixed relation thereto.

The drawings illustrate a standard form of 35 Dayton-Torrington swaging machine of the rotary type with my present improvement applied thereto. Referring to said drawings:

Fig. 1 is a front elevation of such a machine showing in dotted lines the disposition of the roll rack and hammer members;

Fig. 2 is a longitudinal section of the same 40 along line 2-2 of Fig. 1;

Fig. 3 is an enlarged front detail view of the roll rack, spindle head, hammers and dies;

Fig. 4 is a view in perspective of the dies; 45 and

Fig. 5 is a view in perspective of the supplemental hammer members.

Referring more particularly to the drawings: 50 1 is the stationary base support carrying in fixed relation thereto a cylindrical

head 2 recessed at its front face to receive the moving parts of the machine. The spindle 3 is mounted in a bearing (as shown) of the stationary head 2, and has at its rear end fast and loose pulleys 4, and integral with 55 its front end the spindle head 16. 15 is the circular rack mounted for free rotation around the outside of the spindle head 16 and within the recessed portion of the stationary frame head 2. A face plate 8, fixed to the head 2, is also provided to retain the rack in position. The rack 15, as is usual, comprises a plurality of bearing portions for receiving therein loosely the operating rolls 60 17 of the machine. The hammers 18 and the supplemental hammer members 19 are slidably mounted in a diametrically extending groove on the face of the spindle head 16, and the upper ends of said hammer members 65 18 are rounded in the usual manner for co-acting with the opposed rolls 17 carried in the rack 15. In some cases the hammer members 18 and supplemental hammer members 19 may be formed as one integral piece instead of separable as shown. Except for the supplemental hammer members 19, the parts 70 so far described are of standard construction.

As will be noted more particularly in Figs. 3, 4 and 5, the supplemental hammer members 19 are formed on their inner ends with concave bearing surfaces 19a to receive therein the dies 20, which dies are formed with convex semi-cylindrical back surfaces. In this way the dies 20 fit loosely within the 75 opposed faces of the supplemental hammer members 19 to provide a rotative bearing therebetween whereby the dies may be held against rotation during the planetary movement of the hammer members around the same. The front faces of the dies 20 (as shown in Fig. 4) are formed with the impressions for shaping the non-round piece of work to be swaged. In Fig. 3, the work being swaged is indicated at 21. The usual holding plates 5, 6 and 7 are mounted on the face of the spindle head for retaining the hammer members and dies thereon. The holding plate 6 is centrally perforated as 80 shown and the spindle 3 is also made hollow 85 90 95 100 105

so that the work may be introduced between the dies and withdrawn during the operation of the machine.

In operation, the spindle 3 with its head 16 is given a rapid rotation and the hammer members 18 and 19, carried thereby, are brought into successive contact with the opposed rolls 17 by centrifugal forces and are given a pounding action in the usual manner 10 against the dies 20 and the interposed work 21 for swaging the same. Inasmuch as the dies 20 do not partake of the rotary movement, the work acted upon may be held stationary in the hand of the operator during 15 the swaging action thereon and may be introduced and withdrawn during the operation of the machine in the usual manner.

Claims:

1. The combination with a swaging machine having reciprocating hammer members partaking of a planetary movement around the work to be swaged, of a pair of work engaging dies separable from said hammer members and having rotative bearing 25 surfaces in engagement with said hammer members whereby it is possible for the dies to remain non-rotative relative to the work during the operation of the machine.

2. The combination with a swaging machine having reciprocating hammer members partaking of a planetary movement around the work to be swaged, of a pair of work engaging dies separable from said hammer members and having cylindrical 35 bearing surfaces in engagement with said hammer members whereby it is possible for the dies to remain non-rotative relative to the work during the operation of the machine.

3. The combination with a swaging machine having reciprocating hammer members partaking of a planetary movement around the work to be swaged, of a pair of dies separable from said hammer members, said dies having opposed work engaging faces 45 for shaping a non-round piece of work, said faces being so shaped as to hold the work from rotation relatively to the dies and cylindrical back portions fitted in a bearing of the hammer members, whereby the dies may remain non-rotative relative to the work during the operation of the machine.

In testimony whereof I have affixed my signature.

SAMUEL C. CROSS.
